CLAIM

The ornamental design for motorcycle driving lights, as shown and described.

DESCRIPTION

FIG. 1 is a front perspective view of the motorcycle driving lights of the present invention.

FIG. 2 is a front elevation view thereof.

FIG. 3 is a rear elevation view thereof.

FIG. 4 is a left side view thereof.

FIG. 5 is a right side view thereof.

FIG. 6 is a top view thereof; and,

FIG. 7 is a bottom view thereof.

Those portions of the motorcycle driving lights shown in broken lines form no part of the claimed design.
